UNITED STATES PATENT OFFICE.

EUGENE E. LATTA, OF LAFAYETTE, INDIANA.

DESIGN FOR A DISPLAY-JAR.

SPECIFICATION forming part of Design No. 26,321, dated November 24, 1896.

Application filed May 28, 1896. Serial No. 593,515. Term of patent 7 years.

To all whom it may concern:

Be it known that I, EUGENE E. LATTA, a citizen of the United States, residing at Lafayette, in the county of Tippecanoe, State of Indiana, have invented and produced a new and original Design for a Display-Jar, of which the following is a specification, reference being had to the accompanying drawings, forming part thereof.

10 The leading feature of my design for a display-jar is a circular body with a perpendicularly-rising cylindrical discharge-spout, an eye projecting from said neck and having a ring depending therefrom, rearwardly-extending journals projecting from the sides of 15 the body of the jar, and a cover over above the upper end of said spout.

Figure 1 represents a side elevation of a display-jar embodying my design. Fig. 2 represents a front elevation thereof.

In the drawings, A designates the body of a display-jar, the same being circular and closed at all points, excepting at one place in the periphery thereof, where there is an opening, from the walls of which extends tangentially the discharge-spout or neck B, the latter being cylindrical in shape and occupying a perpendicular position on said body. On the exterior of said neck is the ear C, from which depends the ring D. On the sides of 30 the body are journals E, which rest on the stand F, which is extended rearward and has thereon the cover G of said spout B.

What I claim is—

The design for a display-jar, substantially 35 as described and shown.

EUGENE E. LATTA.
